US0D1081677S

(12) **United States Design Patent** (10) **Patent No.:** **US D1,081,677 S**
(45) **Date of Patent:** **** Jul. 1, 2025**

(54) **DISPLAY SCREEN OR PORTION THEREOF
WITH GRAPHICAL USER INTERFACE**

(71) Applicant: **Yahoo Japan Corporation**, Tokyo (JP)

(72) Inventor: **Miyuki Oshima**, Tokyo (JP)

(73) Assignee: **LY Corporation**, Tokyo (JP)

(**) Term: **15 Years**

(21) Appl. No.: **29/823,166**

(22) Filed: **Jan. 14, 2022**

(30) **Foreign Application Priority Data**

Jul. 16, 2021 (JP) 2021-015496

(51) **LOC (15) Cl.** **14-04**

(52) **U.S. Cl.**

USPC **D14/486**

(58) **Field of Classification Search**

USPC **D14/485-495**

CPC **G06F 3/0488; G06F 3/04817; G06F 3/04845; G06F 3/04847; G06T 2200/24; G06T 2207/10024; G06T 2219/2012**
